UNITED STATES PATENT OFFICE.

MARCELLUS HENDERSON, OF WEST HOBOKEN, NEW JERSEY.

PROPELLER.

Application filed October 4, 1922. Serial No. 592,228.

To all whom it may concern:

Be it known that I, MARCELLUS HENDERSON, a citizen of the United States of America, residing at West Hoboken, county of Hudson, State of New Jersey, have invented certain new and useful Improvements in Propellers, of which the following is a specification.

This invention relates to propellers.

Heretofore, it has been common practice to support propellers of ships of the sea as well as for aeroplanes, wholly on the propeller shaft or the engine shaft, and in the event of breakage of the propeller-supporting shaft, the propeller is dropped and lost, with the serious consequences unfortunately repeated too often in the chronicles of the sea and the air.

An object of this invention is to provide the suitable supporting means for the propeller whereby in the event of breakage of the propeller-supporting shaft, the propeller is securely retained and its loss safe-guarded against and independently of the propeller shaft.

A further object of the invention is to provide retaining means for the propeller to partially relieve the propeller-supporting shaft from thrusts and stresses incident to the rotative actuation by the propeller shaft.

A further object of the invention is to provide suitable mounting means for the propeller whereby in the event of partial rupture of the propeller shaft, the shaft may be removed while the propeller is substantially retained in normal position and a new shaft replaced for the propeller. This advantage is of especial merit for ships while at sea in the event of the necessity of repair or replacement of the propeller shaft.

Pursuant to a preferred form of the invention, the propeller is provided with a hub extension, projecting anteriorly of the hub proper of the propeller, which extension is grooved or otherwise provided with

a keying element coacting with suitable mounting means provided with a co-operating keying element whereby upon breakage of the shaft, such keying elements combine to retain or longitudinally lock the propeller in position. Preferably, such mounting means is formed with a removable member to facilitate installation of the propeller and subsequent removal of the propeller.

Further features and objects of the invention will be more fully understood from the following detail description and the accompanying drawings, in which,

Fig. 1 is a perspective view of a propeller embodying my invention;

Fig. 2 is a detail longitudinal sectional elevation on line 2—2 of Fig. 1;

Fig. 3 is a detail side elevation showing the stern of a water craft ship and provided with a propeller embodying my invention; and

Fig. 4 is a sectional elevation on line 4—4 of Fig. 3.

Referring to Fig. 3 of the drawings, my invention is illustrated for use as a propeller for a steamship or other water craft vessel which may be of any approved type. However, it will be understood that the invention is applicable also to airplanes and other ships of the air, turbine wheels, water wheels and like devices.

The counter-stern of the ship is indicated at 10 and the rudder is shown at 11; the rudder may be carried by the rudder post 12, mounted at its lower end in the shoe 13. The stern proper of the ship is indicated at 14.

The propeller shaft 15 extends through stuffing boxes (not shown) located in the usual manner adjacent the face of the stern 14 and extends a proper distance therebeyond to locate the propeller 16 in suitable relation to the ship, as will be understood by those skilled in the art. As is illustrated in Fig. 1, the propeller 16 may be of three-

blade type; the type and number of blades, as well as the formation of the blades may be varied as desired.

The hub 17 of the propeller is provided with the central opening 18 for receiving the end of the propeller shaft 15. Extending anteriorly of the hub 17, I provide the collar 19 which may be cast integrally with the hub 17 or otherwise fixedly secured thereto and provided with a shaft receiving opening 18^a registering with the opening 18 of the hub 17. As illustrated in the drawings, the collar 19 is provided with the peripherally extending groove 20 and in such type of collar the groove 20, as appears more fully hereinafter, co-operates with the suitable securing and mounting means therefor to longitudinally key and thereby retain the propeller 16 in position in the event of partial or complete rupture of the propeller shaft 15.

As one form of supporting and mounting means for the collar 19 of the propeller 16, I have illustrated the bracket 21 formed of juxtaposed members 22, 23, see Fig. 4, respectively provided with the oppositely extending semi-annular portions 24, 25 providing when in position, the opening 26 having a diameter slightly greater than the diameter of the circular face 27, see Figs. 1 and 2, of the groove 20. Such semi-annular portions 24, 25, see Fig. 3, have a width reduced more or less in dimension as compared with the length of the circular face 27 of the groove 20, to thereby reduce frictional losses upon the rotation of the extension 19 incident to the drive of the propeller 16 by the propeller shaft 15, but in the event of breakage or partial rupture of the propeller shaft 15, the extension 19 is retained within the opening 26 of the bracket 21.

Such bracket members 22, 23, are clamped at their upper angular extensions to the counter stern 10 of the ship, as by means of bolts 28, rivets or the like and similarly clamped at their lower laterally angular extending portions 29 to the stern proper 14 of the ship by the bolts 30 or the like. If desired, the bracket members 22, 23 may be intermediately clamped against lateral displacement by means of the bolts 31, 32, which may be located adjacent and on opposite sides of the respective circularly extending portions 24, 25.

The propeller 16 may be locked peripherally on the propeller shaft 15 by a removable key, spline or the like, coupling the extension or collar 19 directly to the propeller shaft 15.

From the above, it will appear under normal actuation of the propeller 16 by the propeller shaft 15, the propeller proper will be rotated to drive the ship 10 forwardly or rearwardly, as will be understood. In

such position of the propeller 16, the extension or collar 19 will idly rotate within the opening 26 of the bracket 21. In the event of partial rupture of the propeller shaft 15, the extension or collar 19 will have a bearing relation with the curved portions 24, 25 of the bracket 21, thereby serving to partially support the weight of the propeller 16 and relieve the disabled propeller shaft of the entire weight of the propeller. In the event of complete rupture or breakage of the propeller shaft 15, the curved portions 24, 25 of the bracket 21 coact with the groove 20—27 of the extension or collar 19 to longitudinally lock and thereby safeguard the propeller 16 from dropping into the sea. The coaction of the groove 20 and collar 19 with its support, such as the semi-annular portions 24, 25 affords a support for the propeller proper 16 independently of the propeller shaft 15, and thereby relieving the propeller shaft 15 of stresses and strains in the normal operation of the drive of the propeller 16 by the propeller shaft 15.

When it becomes necessary or desirable to repair the propeller shaft while the ship is at sea, upon removal of the propeller shaft 15 from connection with the propeller 16, the extension or collar 19 retains the propeller 16 substantially in normal position.

If desired, suitable lubrication may be provided between the bearing faces of the semi-annular portion 24, 25 of the bracket 21 and the bearing face 27 of the collar 19.

In a similar manner, the propeller of an airship may be provided with an extension or collar similar to 19 and suitable bracket similar to the bracket 21 provided for mounting and supporting the collar 19 under normal and abnormal working conditions corresponding similarly to those hereinabove particularly described in relation to a water craft vessel.

Whereas I have described my invention by reference to specific forms thereof, it will be understood that many changes and modifications may be made without departing from the spirit of the invention.

I claim:

1. The combination with a ship having a propeller shaft, of a propeller, removable means for fixedly securing said propeller to said propeller shaft, an extension secured to said propeller, said extension being provided with an opening for reception of the propeller shaft and means carried by the ship for rotatably normally freely receiving said extension and for retaining the same in the event of breakage of the propeller shaft, said mounting means comprising a removable portion to permit said extension to be removed from said mounting means.

2. The combination with a ship having a propeller shaft, of a propeller comprising a hub and blades, removable means for fixedly securing said propeller to said propeller shaft, an extension fixedly secured to said hub and mounting means carried by said ship for rotatably normally freely receiving said extension, said extension and said mounting means coacting to lock one another against longitudinal parting, in the event of breakage of the propeller shaft said mounting means comprising a removable portion to permit said extension to be removed from said mounting means.
- In testimony whereof I have signed this 6th day of September, 1922.

MARCELLUS HENDERSON.
